DESIGN FOR A FILE BOX

Gilbert Stanley Underwood, Washington, D. C.

Application December 9, 1946, Serial No. 135,362

Term of patent 3½ years

(Cl. D74—1)

To all whom it may concern:

Be it known that I, Gilbert Stanley Underwood, a citizen of the United States, residing in Washington, District of Columbia, have invented a new, original, and ornamental Design for File Boxes, of which the following is a specification, reference being had to the accompanying drawings, forming a part thereof.

In the drawings:

Figure 1 is a perspective view of the file box showing my new design.

Figure 2 is a cross section on the line 2—2 of Figure 3.

Figure 3 is a front elevational view thereof.

My design for a file box is characterized by having three pockets, the lowermost having a horizontal bottom with an upturned front edge, an intermediate pocket above said lower pocket having a rearwardly inclined bottom with an upturned edge, an upper pocket with a rearwardly inclined bottom at an angle greater than the in-

termediate bottom, and provided also with an upturned edge, two curved side walls, a vertical rear wall forming a back for said upper pocket, a relatively narrow top extending forwardly of said rear wall, a label holder on the front edge of each pocket and transverse walls fixing the depths of said lower and intermediate pockets.

I claim:

The ornamental design for a file box, as shown and described.

GILBERT STANLEY UNDERWOOD.
